VALUABLE-PAPER WALLET

George Seelman, Jr., Milwaukee, Wis., assignor to
George Seelman & Sons Co., Milwaukee, Wis., a
corporation of Wisconsin

Application April 9, 1930. Serial No. 442,788

2 Claims. (Cl. 129—41)

The invention relates to wallets or holders for valuable papers and the like.

An object of the invention is to provide a wallet or holder including means for detachably securing therein a plurality of filing envelopes or other folders or sheets, and having an extension cover which not only permits a variable number of envelopes to be accommodated within the wallet, but also serves as a means for retaining the group of envelopes in close relation.

Another object of the invention is to provide a wallet of this character in which a plurality of parallel flexible thongs are each secured at their opposite ends to one of the cover members for detachable connection with edge portions of the envelopes, the other cover member serving to enclose those end portions of the thongs unoccupied by the envelopes.

The invention further consists in the several features hereinafter set forth and more particularly defined by the annexed claims.

In the accompanying drawing, Fig. 1 is a perspective view of a closed wallet constructed in accordance with the invention;

Fig. 2 is a side edge view of the closed wallet, parts being broken away and parts being shown in section, and an extended position of one of the cover members being shown in dotted lines;

Fig. 3 is an inside view of the wallet as it appears when in open position and with the envelopes removed, parts being broken away and parts being shown in section;

Fig. 4 is a detail plan view of one of the filing envelopes, and

Fig. 5 is a fragmentary detail perspective view of one of the envelopes taken along the line 5—5 of Fig. 4.

In the drawing, the numerals 10 and 11 designate the cover members of a wallet embodying the invention. The cover member 10 is provided with a flexible portion at one end forming a bendable flap 12 of reduced thickness adapted to slidably fit within the cover member 11, which latter member has double walls to form a sheath for this purpose. The sheath has an entrance slot into which the flap is inserted. A flexible strap 13 is fixedly secured at one end within the medial outer portion of the flap 12 and slidably extends within the sheath-like cover member 11 from which it emerges through a slit-like opening 14 formed in the outer edge of this cover member. A suitable fastener or latch 15 is secured to the outer face of the cover member 10 to adjustably receive the free end portion of the strap, as seen in Figs. 1 and 2.

As in the device shown and described in United States Patent No. 1,522,146 to Henry Seelman, granted January 6, 1925, the strap 13 serves to adjustably draw the flexible flap into the sheath-like cover member and to retain the cover members in closed position. The wallet of the present invention, however, differs from the device of the above-noted patent in several features of construction hereinafter described.

A pair of spaced flat parallel flexible thongs 65 or strips 16 are secured at their opposite ends to the inner face of the cover member 10, as by means of tubular rivets 17, one end of each thong being located near the outer edge of the flap 12, and the other end of the thong being located on the thicker portion of the cover member and near the flap. The flap with its attached thongs is inserted into the entrance slot of the sheath.

The thongs 16 are adapted to receive thereon the edge portions of sheets or folders 18 which are here indicated to be envelopes adapted to receive valuable papers. For this purpose one edge portion of each envelope is provided with spaced thong-receiving openings 19, there being slits 20 extending between the openings and the edge of the envelope to permit the mounting and removal of the envelope. The openings 19 and slits 20 also pass through a folded or doubled strip of fabric 21 which is pasted within the envelope along the apertured edge portion thereof.

The apertured edge portion of the envelope is thereby made relatively firm so that the openings 19 can be placed relatively close to the edge of the envelope. The edge portions of the envelope adjacent each slit 20 form narrow resilient tongues 22 which resist outward movement of the envelope from its thongs but which can be laterally displaced in opposite directions to permit the passage of the thong into or out of the opening 19. The adjacent free ends of each pair of tongues 22 are practically in engagement. The envelopes may be of a type shown in my co-pending application for Letters Patent for Filing envelopes, Serial No. 442,789, filed April 9, 1930, now matured into Patent No. 1,777,452, dated October 7, 1930.

When the envelopes are to be placed in the wallet, the wallet is opened and the sheath-like cover member 11 is moved outwardly along the flexible end flap 12 of the cover member 10, thereby exposing the thongs 16. The envelopes are then mounted on the thongs 16, and the sheath-like cover member 11 is then pushed inwardly along the flap 12 of the cover member 10 approximately as far as it will go, the relative inward

movement of the cover members being limited by the thickness of the group of envelopes on the thongs. The wallet may then be closed to the position of Figs. 1 and 2. When it is necessary to add envelopes it is only necessary to open the wallet and again withdraw the cover member 11 along the flap 12, whereupon additional envelopes may be snapped onto the thongs. The cover member 11 is then again slid inwardly along the flap 12 to cover the end portions of the thongs unoccupied by the envelopes. The frictional engagement of the cover member 11 with the flap 12 serves to restrain relative sliding movement of these parts when the wallet is opened for access to the envelopes.

By means of the reenforced resilient tongues 22, the envelopes will not become accidentally dislodged from the thongs even though the envelopes are loosely mounted on the thongs, and since the adjacent end portions of each pair of tongues are in contact or very nearly so, it is possible to use thin narrow ribbon-like flexible thongs without danger of accidental separation of the envelopes from the thongs. The tongues 22 and thongs 16 form the sole means resisting outward pull on the envelopes when the wallet is open.

When the wallet is closed the ends of the thongs secured to the thicker portions of the cover 10 lie parallel to and adjacent the outermost envelope, as seen in Fig. 2, to minimize shifting of the envelopes on the thongs, and when the wallet is opened the envelopes may slide loosely on the thongs and will lie substantially flat when swung in either direction, without need for shifting cover 11 with respect to the cover 10. The

loose mounting of each envelope on the thongs facilitates the filing of papers in the envelope and increases the useful size of the envelope.

What I claim as new and desire to secure by Letters Patent is:

1. In combination, a binder including a cover member having a flexible flap, a second cover member forming a sheath adjustably receiving said flap therein, a plurality of parallel flexible strips secured at their outer ends to said flap and at their inner ends to the inner face of said first named cover member adjacent said flap, said flexible strips being adapted to receive apertured sheets, the outer portions of said strips unoccupied by said sheets being enclosed within said sheath-forming cover member, and the inner portions of said strips lying parallel to and adjacent an outermost sheet when the binder is closed to minimize shifting of said sheets, said inner portions of said strips when the binder is open permitting loosening of the sheets therealong and allowing the sheets to lie substantially flat when swung in either direction.

2. A binder comprising a cover having a flexible back-forming flap, a second cover having a sheath presenting a slot, and a plurality of parallel flexible strips secured to said first cover at the inner face of said flap and transversely of the flexing lines of said flap and having end portions attached to said flap, said strips being adapted to hold apertured sheets thereon, and said flap with its attached strips being insertible into the slot of the cover sheath and being movable in said sheath to adjustably expose said flap and strips.
